JASON C. LOTTERHAND, OF NEW YORK, N. Y., ASSIGNOR TO ADDOMETER CORPORATION, OF NEW YORK, N. Y., A CORPORATION OF DELAWARE.

ROLL-HOLDER FOR CALCULATORS.

1,158,519.

Specification of Letters Patent.

Patented Nov. 2, 1915.

Original application filed February 24, 1908, Serial No. 417,352. Divided and this application filed November 27, 1914. Serial No. 874,109.

To all whom it may concern:

Be it known that I, JASON C. LOTTERHAND, a citizen of the United States, and a resident of New York city, in the county of New York and State of New York, have invented certain new and useful Improvements in Roll-Holders for Calculators, of which the following is a specification.

This application is divided out of an application filed by me February 24, 1908 Serial No. 417,352.

The object of the present invention is to provide a form of roll holder for use in calculators, and other forms of printing mechanism employing a platen or similar printing surface, whereby rolls of different widths can be supported at the rear of the platen by swinging arms, and which arms besides being adjustably connected with the carriage, can be shifted to permit the arms to be both swung inwardly and be held against the rear of the carriage when not in use.

In the accompanying drawing showing one embodiment of my invention, Figure 1 is a plan view showing the rear portion of a calculator with the platen and carriage, and the roll holder supporting a roll. Fig. 2 is a partial rear view of the supporting bar and roll holder. Fig. 3 is a horizontal section on the line 3—3 of Fig. 2; and Fig. 4 is an end view of the parts shown in Fig. 1.

In the drawings, 270 represents a supporting member at the rear of a calculator, or other printing machine, on which is mounted a carriage denoted generally by 276, that may be slideable on the machine through ball-bearings 284. The carriage as shown is provided with the usual platen 283 rotatably mounted thereon.

At the rear of the carriage are pivotally mounted a pair of arms 320, swinging on blocks 319. These blocks are mounted to slide longitudinally on the carriage each at one side of the middle portion, whereby the arms can be brought to a parallel position at different distances apart to support a roll 300. The blocks 319 are also arranged to recede sufficiently to permit the arms to be swung inwardly and lie against the supporting member of the carriage; and are preferably retained in this position by springs at the hinges.

In the specific arrangement shown, a bar

270 at the rear of the carriage contains a slot 279 whose side walls are overhung, the slot being dovetailed in section, as indicated in Fig. 2. The blocks 319 are similarly shaped to slide in this slot 279. The arms 320 are hinged or pivoted to these blocks to swing on a vertical axis, and each arm is provided with a pin 323 on the inner face, at its outer end; for the purpose of entering the bore of the roll 300 and rotatably support the same. The hinge of each arm 65 is provided with a suitable spring, such as a coil spring 321. These springs will obviously press the arms inwardly or toward the roll 300 for supporting it, to have its web feed to the platen. It will also be understood that when the roll is used up, or removed, the blocks 319 are caused to recede or moved outwardly, and the coil spring will swing the arms in against the bar 279, and the pin 323 will enter the slot 279. If desired apertures 324 may be provided in the bar 270, to receive the pins 323.

It will thus be seen that a very simple and economic arrangement is provided, that is quickly adjustable for different sized rolls; and when not desired for use, the arms are compactly folded inwardly into or against the carriage and retained in such position by the springs ready for instant use.

Having thus described my invention what I claim is:

1. In a printing machine, the combination with a carriage and a platen thereon, of a bar at the rear of the carriage having a horizontal guide-way extending on both sides of the middle of the carriage, a pair of blocks slidably mounted in the guide-way one on each side of the middle portion, an arm hinged to each said block, and a lug on the inner face of each arm at its outer end, the blocks being slideable to permit the arms to extend transversely rearward in parallelism to support rolls of different widths, the blocks being slideable also to recede and permit the arms to be folded inwardly to both lie against the guide-way, substantially as set forth.

2. In a printing machine, the combination with a carriage and a platen thereon, of a bar at the rear of the carriage having a horizontal guide-way extending on both sides of the middle of the carriage, a pair of blocks slidably mounted in the guide-way

one on each side of the middle portion, an arm hinged to each said block, a lug on the inner face of each arm at its outer end, and a coil spring on each said hinge, the blocks being slidable to permit the arms to extend transversely rearward in parallelism to support rolls of different widths, the blocks being slidable also to recede and permit the arms to be folded inwardly by the springs and both be held against the guide-way, substantially as set forth.

3. In a printing machine, the combination with a carriage and a platen thereon, of a bar at the rear of the carriage having a horizontal guide-way extending on both sides of the middle of the carriage, a pair of blocks slidable mounted in the guide-way one on each side of the middle portion, an arm hinged to each said block, a lug on the inner face of each arm at its outer end, and a coil spring on each said hinge, the blocks being slidable to permit the arms to extend transversely rearward in parallelism to support rolls of different widths, the blocks being slidable also to recede and permit the arms to be folded inwardly by the springs and both be held against the guide-way, the bar having apertures at the middle portion to receive the lugs when the arms are folded against the carriage, substantially as set forth.

JASON C. LOTTERHAND.
